UNITED STATES PATENT OFFICE

JACOB W. HARTMAN, JR., OF FORT WAYNE, INDIANA, ASSIGNOR TO WAYNE COMPANY,
OF FORT WAYNE, INDIANA, A CORPORATION OF INDIANA

DESIGN FOR A FLUID DISPENSING APPARATUS

Application filed February 29, 1932. Serial No. 43,034. Term of patent 7 years.

To all whom it may concern:

Be it known that I, JACOB W. HARTMAN, JR., a citizen of the United States, residing at Fort Wayne, in the county of Allen and State of Indiana, have invented a new, original, and ornamental Design for a Fluid Dispensing Apparatus, of which the following is a specification, reference being had to the accompanying drawings, forming a part thereof.

Figure 1 is a front elevation of the article showing my new design, the article being substantially the same on the opposite side thereof; and

Figure 2 is a side elevation of the article shown in Figure 1.

I claim:

The ornamental design for a fluid dispensing apparatus as shown and described.

JACOB W. HARTMAN, JR.
